SORTING MACHINE

Clair D. Lake, Binghamton, N. Y., assignor, by
mesne assignments, to International Business
Machines Corporation, New York, N. Y., a cor-
poration of New York

Application December 19, 1932, Serial No. 647,915

5 Claims. (Cl. 209—110)

The invention relates to card controlled ma-
chines in general and more particularly to those
adapted to sort record cards such as are used
to control the operation of the well known Hol-
5 lerith type of tabulating machine.

The primary object of the invention is to pro-
vide a novel means for sorting into separate
pockets, groups of cards in which the component
10 individual cards are arranged in a predetermined
order. In certain classes of work groups of
cards are arranged with a "first master card"
as the first card of the group. This "first master
card" has a cut corner in what will hereinafter
15 be termed the lower left corner. This card is
also perforated in a selected field with data for
controlling the selection of the pocket to re-
ceive the entire group. Following the "first
master card" are a variable number of detail
20 cards with their upper left corners cut. The
last card in each group is called the "second
master card" and has all four corners square.

The specific object of the invention then, is
to sort the complete group of cards into a pocket
determined by the perforated "first master card"
25 which will set the machine to feed all follow-
ing cards into the same pocket including the
"second master card", which restores the setting
in preparation for a new selection by the "first
master card" of the following group.

30 Various other objects and advantages of the
invention will be obvious from the following
particular description of one form of mech-
anism embodying the invention or from an in-
spection of the accompanying drawings; and the
35 invention also constitutes certain new and novel
features of construction and combination of
parts hereinafter set forth and claimed.

In the drawings:

Fig. 1 shows the wiring diagram of the com-
40 plete electric circuits of the machine, the me-
chanical elements of which have been diagram-
matically illustrated and show the elements of
a sorting machine as set forth in greater detail
in Patent No. 1,741,985.

45 Fig. 2 is a diagram showing the order of ar-
rangement of the several cards of a representa-
tive group.

Before proceeding with the description of the
invention, the sorting machine will be briefly ex-
50 plained as to its general principles. Fig 1 shows
an electrically controlled sorting machine in
which the sorting of the record cards is ac-
complished through the medium of a sorting
magnet 11 under the control of a brush relay
55 10 which, jointly with the sorting magnet, is in

circuit with the sorting brush 22 and, with the
sorting magnet, receives exciting current from a
source 17 as soon as a hole is encountered in the
card column analyzed. According to the point
of time at which the energization of the sorting
5 magnet 11 takes place, the armature 23, upon
which the ends of the tongues 24 of the guide
blades leading to the card receiving pockets 25
rest, determines the destination of the card being
analyzed.

The ends of the tongues 24 are spring-urged
downwardly by their own resiliency upon the
armature 23 so that during the card analyzing
cycle the record card is guided between the
ends of the tongues 24 and the armature 23, with
10 the result that upon the energization of the sort-
ing magnet 11, only as many tongues 24 are
lowered by the armature as do not overlie the
record card, while the remaining tongues 24
15 are kept in raised position by the card itself.
For this purpose there is provided a fixed bar 26,
parallel to and on a level with, the armature 23
when in its normal position, arranged to support
the record card after the armature 23 is lowered.
It may be mentioned that the time of energiza-
20 tion of the sorting magnet depends upon the
position of the hole in the card column, each of
which has twelve index point positions, so that
the cards may be guided selectively into any
25 one of the twelve sorting pockets 25.

30 Through the downward movement effected by
energization of the sorting magnet, the tongues
24 disengaged from the card produce a gap be-
tween the last tongue held up by the record
card and the next adjacent tongue moved down-
35 ward along with the armature 23, into which
gap the record card is conveyed and thereafter
guided to the coordinated sorting pocket by
means of the usual feeding rollers 27.

If it should happen that there is no perfora-
40 tion in the card column analyzed, the magnet
11 will not be energized, and the card will pass
beneath all of the tongues 24 and will be guided
to a thirteenth pocket 25R known as the "reject"
pocket. The card feeding mechanism comprises
45 a picker 28, horizontally reciprocable to feed
cards, singly, from the bottom of a stack 29 to
a pair of feed rollers 30 which advance the card
to and between brush 22 and contact roller 31.

The drive of the machine is effected by means
of a motor M which is under control of motor
50 relays 32 and 33 in such manner that upon the
energization of the relays, the motor is con-
nected to the current source 17. Energization of
relays 32 and 33 is effected through depression
55 10 which, jointly with the sorting magnet, is in

of the start key to close contacts S, setting up a circuit from negative side of source 17, wire 34, contacts S, card lever relay 35, relays 32 and 33, wire 36 to positive side of source 17. Relay 35 closes its points 35a in series with the usual card lever contacts 37 and forms a shunt around contacts S so that as long as cards continue to run through the machine, the energization of relays 35, 32 and 33 will be maintained. After the last card has passed the brush 22 and the card lever contacts 37 have opened, or the stop key contacts ST have been opened, the deenergization of relays 35, 32 and 33 is effected, in consequence of which the motor M will be disconnected from the current source 17 and the machine will thereafter come to rest.

In order to secure proper operation of the sorting machine, it is necessary that the sorting magnet remain energized from the moment at which energization takes place until the last index point position in the card column has passed beneath the brush 22. The winding of the brush relay 10 is connected in series with the sorting magnet 11 and is energized therewith as soon as a hole is encountered in the card column analyzed and corresponding to the adjustment of the contact segments 12 of commutator 13. There are twelve segments 12 and these successively contact with a brush 14 which is connected by a wire 15 to the brush 22 through a switch 15a which is closed for normal sorting operations. Commutator 13 also has a common wiping brush 16 connected to the brush relay coil 10 through a wire 18 and resting against a metallic ring 19 which is electrically connected to a commutator segment 20 which cooperates with a brush 21. The commutator 13 which is synchronized with the speed of passage of the cards, moves its segments 12 past brush 14, one for each index point position of the card.

During the passage of the card past the usual sorting brush 22, the card hole in the column analyzed coincides with the wiping of the corresponding segment 12 of the commutator 13 and as may be seen from Fig. 1, energization of the brush relay 10 and sorting magnet 11 will be effected.

The foregoing outlines the usual operation of a sorting machine and if switch 15a is closed and switch 38 opened, ordinary sorting may be performed by the machine.

For the functioning of the machine in accordance with the present invention, switch 15a is opened and switch 38 closed. Additional commutators 39, 40 and 41 are provided which may be mounted coaxially with commutator 13 to make one revolution per card cycle therewith. A commutator brush 42 may also be carried by the same shaft to cooperate with a stationary commutator 43 to control circuits in a manner to be presently explained.

An additional brush 44 is provided in line with brush 22 and located to traverse one edge of the cards as they pass through the machine.

Fig. 2 shows the arrangement of a representative group of cards in their order of passage through the machine; M1 is the leading card of the group or the "first master card"; D represents the variable number of detail cards; and M2 is the last card of the group or the "second master card." The regular sorting brush 22 is positioned to traverse a perforated column on card M1. Brush 44 is in line with the cut corners of the several cards.

Assuming now that the group of cards of Fig.

2 has been placed in the machine, depression of the start key will cause feeding of card M1 from the bottom of the stack, advancing its leading edge toward the tongues 24. If the card lever contacts 37 are closed thereby (which occurs before the cards reach the first tongue 24) a circuit is completed when the leading edge of the card M1 is in the dot and dash line position of Fig. 2 as follows: From source 17, wire 34, contact roller 31, brush 44, wire 45, brush 46 of commutator 39, ring 48, contact segment 47, integral with ring 48, brush 49, card lever contacts 31a, relay coils 50, 51 and 52, wire 53 to source 17. Relay 50 closes its points 50a to provide a holding circuit from source 17, wire 53, coils 52, 51, 50, points 50a, wire 54, brush 55 of commutator 40, brush 56, wire 34 to source 17. This circuit will hold until near the end of the cycle. Relay 51 closes its points 51a which bridge the now open switch 15a to permit completion of the sorting magnet circuit through a perforation in card M1.

Assuming a perforation in the "8" position in the column traversed by brush 22, a circuit is now completed from source 17, wire 34, contact roller 31, hole in the "8" position, brush 22, wire 15, points 51a in wire 15, brush 14, "8" segment 12, ring 19, brush 16, wire 18, brush relay 10, wire 57, sorting magnet 11, wire 53 back to source. The tongues in advance of the card will thereupon be lowered and the card will continue into the gap so provided and will be conducted to the "8" sorting pocket 25.

At the same time a parallel circuit will extend from source 17, wire 34, roller 31, brush 22, wire 15, brushes 14, 16, wire 58, switch 38, commutator brush 42, "8" segment 59, its wire 60, "8" relay 61, wire 53, back to source 17. A holding circuit then extends from source 17, wire 34, brush 62, of commutator 41, brush 63, wire 64, "8" relay points 61a, "8" coil 61, wire 53, back to source 17.

Since the points 10a of brush relay are closed and remain so until the end of the cycle, each of the succeeding magnets 61, namely "7", "6", "11" and "12", are energized in turn as brush 42 engages the corresponding segments 59. The circuits therefor are traceable from source 17, wire 34, relay contacts 10a, brush 21, segment 20, ring 19, brush 16, wire 58, switch 38, brush 42, segments 59, wires 60, coils 61 to source as before.

Near the end of the cycle the insulating strip on commutator 41 breaks the holding circuit of magnets 61 but points 52a of relay 52, which are now closed and are wired in parallel with brushes 62, 63 of commutator 41, shunt the brushes and maintain the circuit so that the breaking by commutator 41 is ineffective at this time. The broken holding circuit is again made as soon as brushes 62, 63 ride on the conducting portion of commutator 41 and immediately thereafter the insulating strip of commutator 40 breaks the connection between brushes 55, 56 and the holding circuit traced above breaks to cause deenergization of magnets 50, 51 and 52.

At this time, card M1 is being advanced toward the "8" pocket and the first detail card D is approaching the sensing position. As the card D passes under brush 22, no sorting circuit can be completed through the brush since relay points 51a are open and it will be noted that their closure is necessary to complete a circuit through brush 22.

However, when the "8" index point position of

card D is in line with the brushes, a circuit is completed through the sorting magnet 11 which is traceable as follows: From source 17, wire 34, brushes 62, 63 of commutator 41, wire 64, 5 points 61a in the "8" position, "8" segment 59, brush 42, switch 38, wire 58, wire 18, brush relay 10, wire 57, sorting magnet 11, wire 53, back to source 17. The "8" sorting pocket will thereby be selected to receive the card D and it will 10 ultimately reach such pocket. When its "12" index point position is in line with the brushes, brush 44 will be in contact with roller 31 because of the cutaway upper left hand corner of the detail card, so that when the insulating strip 15 on commutator 41 again attempts to break the holding circuit of magnets 61 at this time, another parallel shunt circuit effective at the 20 cut corner of the card D and running through brush 44 will keep magnets 61 energized until commutator 41 again assumes control. This shunt circuit is traceable as follows: From 25 source 17, wire 34, roller 31, cut corner of card D, brush 44, wire 45, brush 46, ring 48, segment 65, brush 66, wire 67, wire 64, points 61a, magnets 61, wire 53 to source 17.

In this manner, the setup of magnets 61 will be maintained as long as detail cards D continue to be fed past the brushes, commutator 41 attempting to drop the holding circuit each cycle 30 and the cut corner of the detail card rendering the efforts of the commutator ineffective. The last card of the group, namely M2 which has no cut corner, will not shunt the holding circuit and relays 61 will be deenergized after the 35 "8" pocket has been selected for card M2.

Summarizing briefly, the first master card M1 renders the sorting brush 22 effective to select a pocket in accordance with the location of the perforation in a selected card column 40 and to set up relays 61 accordingly. During the subsequent feeding of one or more detail cards, the relay setup automatically selects the same pocket for each detail card and the cut corner of each detail card in turn acts to preserve the relay setup to select the pocket for 45 the next succeeding card.

The last master card M2 since it has no cut corner is unable to preserve the setup which may then be restored by commutator 41 thereby 50 returning the entire circuit to its original condition in readiness to be adjusted under control of the first master card M1 of the next group.

It will be noted that if the card M1 of the 55 following group is missing, all of the cards in that group will go to reject pocket 25R, passing beneath all the tongues 24. This takes place because the cut corner in the leading edge of M1 is necessary to condition the sorting magnet circuit for effective operation as outlined above.

While there has been shown and described and pointed out the fundamental novel features of the invention as applied to a single modification, it will be understood that various omissions and substitutions and changes in the 60 form and details of the device illustrated and in its operation may be made by those skilled in the art without departing from the spirit of the invention. It is the intention therefore to

be limited only as indicated by the scope of the following claims.

What is claimed is as follows:

1. In a sorting machine having a plurality of sorting pockets, means for successively reading the cards of a group, means set in operation by the reading means upon reading the first card of the group, for selecting a pocket to receive said group, a device settable in accordance with the pocket selected, means for suppressing the reading of subsequent cards of the group and means controlled by said device for repeatedly selecting a pocket for each of the other cards of the group. 10

2. In a sorter, means for reading tabulating cards, means controlled by said reading means to sort the cards in accordance with their designations, a device for controlling said sorting means independently of and subsequently to said reading means, means controlled by said reading 15 means for setting said device in operation and further means for suppressing the operation of said reading means while said device is in operation. 20

3. In a sorting machine having more than two pockets, means for feeding a group of cards the number of whose individual cards may be varied and which is preceded by a control card, card reading means, means for determining the presence of a control card at said reading means, 30 means controlled by said determining means for causing said reading means to select any one of said pockets for said group in accordance with data designations on said control card, a device concurrently set up by said reading 35 means, selector means controlled thereby for repeatedly selecting said pocket a number of times equal to the number of cards following the control card to receive each of the remaining cards of the group in succession and means 40 controlled by the last card of the group for terminating the selecting operations of said device. 45

4. In a sorting machine, a plurality of sorting pockets, means controlled by perforated cards for selectively depositing such cards into said 50 pockets, means controlled by said selective means for causing a plurality of cards following a control card to be fed into the pocket selected by said control card said last named means including a plurality of relays corresponding in number to said pockets, a commutator and a circuit jointly controlled by said commutator and the relay associated with the selected pocket for controlling the disposition of cards following 55 said control card.

5. In a sorting machine having more than two pockets, means for reading tabulating cards, a circuit controlled by said reading means, means controlled by said circuit for sorting the 60 cards selectively into any one of said pockets, a selector device for controlling said circuit independently of the reading means to cause said sorting means to subsequently repeat its operation under control of said selector device, means for continuing the repeated operation of said device and means controlled by the cards for determining the number of repeated operations. 65
